Specification of Letters Patent.

Patented Aug. 6, 1912.

Application filed May 4, 1911. Serial No. 624,954.

To all whom it may concern:

Be it known that I, THOMAS F. PAYNE, a citizen of the United States of America, residing at Pittsburgh, in the county of Allegheny and State of Pennsylvania, have invented a new and useful Improvement in Flushing-Valves, of which the following is a full, clear, and exact description, reference being had to the accompanying drawings, which form part of this specification.

This invention relates to flushing valves adapted for use in connection with water-closets, lavatories, and similar sanitary apparatus, and more commonly to that type of valve in which the main valve which controls the source of supply is operatively reciprocated by differential of water pressure and flow which is controlled by a secondary valve or release mechanism.

The invention aims to provide a simple, durable and inexpensive improved construction therefor, and among the objects contemplated by it are the provision of a device in which sticking of the valve, due to imperfect centering, is prevented and the provision of a fitting or casing by means of which the relief valve is compactly mounted in a chambered cap portion and also a fitting by means of which leakage from the discharge chamber is overcome.

I will now describe my invention so that others skilled in the art to which it appertains may understand and construct the same, it being premised, however, that various changes may be made in the construction of the valve shown in the accompanying drawings without departing from my invention.

Figure 1 is a vertical sectional view of an upright valve made in accordance with my invention, the main valve being seated; Fig. 2 is a similar view of the valve showing the valve in open or flushing position; Fig. 3 is a section through the valve casing on the line 3-3 of Fig. 2; Fig. 4 is an enlarged fragmentary view showing portions of the main plunger and of the relief valve; and Fig. 5 is a view corresponding with Fig. 1 but showing a reversal of the discharge and inlet passages with attending modifications of structure.

In Figs. 1, 2, 3, and 4 the valve casing or fitting 2 is shown as cylindrical in form and has, at its lower end, the ingress or inlet passage 3 which may be coupled to a suitable source of supply. Within the

chamber 4 of the casing is a valve 5 which controls the supply port 3 through its engagement with the seat 6 and has the depending stem-like portion 7 which passes through the centering or guide-arm 8 diametrically carried in the port 3 by the casing. From the side of the casing leads the discharge port 9 which may be coupled by the suitable pipe 10 to a closet-bowl or other apparatus to be flushed, and in communication with this discharge port 9 at a point outside of where the said discharge port 9 communicates with the chamber 4 is the discharge vent 11 which leads from the chamber 12 of the cap 13 which has screw-threaded engagement with the top of the casing. This cap 13 has the annular channel 14 provided with the perforations 15 through which the relief water is discharged into the said chamber 14 and thence to the passage way or vent 11. The cap 13 is shown as having the packing 16 and 17 by means of which sealing is effected between the upper part of the casing 2 and the associated faces of the cap. It has been found, however, that unless the packing at the top of the cap and between the cap and the lower portion of the cap and fitting is renewed quite often, there is a leakage or seepage between the cap and the casing, which is very undesirable; so, to overcome this leakage I have caused the discharge passage way 11 to communicate with the discharge port 9 substantially at a point outside of the casing, as above described, so that there shall be created by the flow of the solid stream of water through the port 9 a suction or siphonic action which will effectively drain all water from the upper portion of the casing or the discharge chamber; the port 9 being so formed at its point of communication with the chamber 4 that there is provided a depending wall or baffle 9' which projects down into the passage way of the port 9 on the upstream side with respect to, passage 11 sufficiently to prevent the flow of water into the passage way 11, the said baffle serving to guide or direct the body of the stream in a straight line to the exterior portion of the port. The passageway 11 is contracted at its delivery end to a port 11^a of relatively small area, so that the down rushing water is ejected in a solid jet into the discharge passage 9. This jet formation insures a siphonic pull and proper suction

in the drainage passage 11 and chamber 12, so as to effect proper and complete drainage; which would not be the case if the water fell in a broken stream from the chamber 12 to the discharge passage 9 through the large passageway 11. The lower portion 13' of the cap 13 forms a dividing wall between the chamber 4 of the casing 2 and the chamber 12 of the cap 13, and disposed therein is a relief port 18 which has the seat 19 against which seats the valve 20 which is terminally carried by the stem 21. Said lower portion or web 13' of the cap 13 is upwardly bulged or crowned, 15 as shown, so as to drain naturally toward the ports 15 and channel 14, the water flowing through the relief port 8 when valve 20 is opened; thereby insuring complete draining of water from the chamber 12. Within 20 the chamber 12, on the stem 21, is a fixed collar 22 between which and the seat 23 concentrically formed with the port 18, is the interposed coiled spring 24 which serves to normally hold the valve 20 against the seat 19. The stem 21 is reciprocally carried by 25 the cap 13, said stem passing upwardly through the double stuffing box 25 and having at its upper end the suitable pushbutton 26 by means of which the stem may be depressed to unseat the valve 20 when it is desired to open communication between the chamber 4 and the chamber 12. Between the wall 13' of the cap 13 and the lower portion of the chamber 4 is the piston 27 which 30 comprises the head portion 28 and clamping screw 29 between which lies the disk 30 which serves to back up the cup leathers 31 symmetrically disposed on opposite sides thereof. To this piston 27, by means of the head or body portion 28, is secured the valve 5, and centrally passing through the valve 5 and piston 27 is the small inlet passage 32 which leads into the chamber 4 between the piston 27 and the lower portion 13' of the 35 cap 13. Carried by the clamping screw or disk 29 is the central adjusting screw 33 to limit the travel of the piston 27, and this adjusting screw has the central bore 34 by means of which the communication of the 40 passage 32 with the chamber 4 above the piston 27 is effected. The bore 34 is somewhat restricted or smaller than the passage 32 and projecting thereinto is the pin 35 carried by the lower end of the stem 21. 45 The purpose of this pin is to act as a wiper, removing any particles of dirt which may lodge in the inlet passage. The wiping action is effected not only by the reciprocation of the plunger but also by the downward 50 stroke of the stem 21 when the valve 20 is forced from its seat. The upper end of the screw 33 has the cross-cut or kerf 36 which leaves the passage way 32 in open communication with the chamber 4 above 55 the piston 27 when the screw 33 ascends with

the piston 27 into abutment with the lower end of the stem 21 or valve 20 as the valve 5 is caused to be elevated or opened to flushing position. In this type of valve the valve 5 normally closes the port 3 of the source of supply by reason of the pressure of the water back of the large piston 27 as against the pressure of the water against the relatively small differential faces 37 of the valve 5. With the depression of the stem 21 and resultant lowering of the valve 20 from its seat 19, the water bound in the chamber 4 above the piston 27 escapes through the port 18 to the discharge chamber 12 and then to the passage way 11 to the main discharge or outlet 9. This relief of the pressure upon the top of the piston 27 causes the said piston 27 to ascend within the chamber 4 by reason of the pressure of the water against the valve 5, as shown in Fig. 2. When the valve is in this open position the water passes from the port 3 into the lower part of the casing 2 to the lateral discharge port 9 for flushing the closet or other apparatus, and by this flow of water into the passage 9 there is created, as above stated, a suction or siphonic action within the chamber 11 which causes the water within the chamber 12 at the top of the casing to be thoroughly drained therefrom. As the water passes into the passage way 3 it gradually feeds through the small passage way 32 of the valve 5 and piston 27 into the upper part of the chamber 4 where it exerts its pressure upon the piston and thereby causes the valve 5 to be returned to its normal position on the seat 6. When the valve 20 is forced from its seat for the discharge of the water bound in the upper part of the casing, it is immediately returned to closed position by the spring 24. With the valve 5 being provided with the flat stepped or differential faces 37, the incoming water is gradually choked or cut off by successively decreasing stages so that there remains a steady gradually reducing stream until the valve is completely closed, to fill the bowl.

In Fig. 5 I have shown the casing or fitting as having the inlet and flushing ports in a reverse position to that of the preceding views. In this view, the discharge passage 11' communicating with the main discharge or flushing port 3', corresponds in function to the passage way 11 of Figs. 1 and 2. The piston 27 is shown as having the angular or lateral entrance 40 to the passage way 32 instead of having the passage 32 extending to the full limit of the valve and its stem, for the reason that the lower part of the casing has become the discharge port 3' while the inlet port 9' assumes the discharge port position in the side of the casing. In this case, the baffle wall 41 corresponds to the wall 9' of Figs. 1 and 2, and it will be noticed that the guide arm 8 lies at right 115 120 125 130 135

angles to and out of the way of flow from the passage 11' so as to permit the discharge water to pass the wall 41 and mouth of the passage 11', in a solid uninterrupted stream and thereby cause a suction or drawing action in the passage 11'. The remaining construction of the valve is the same as that of the preceding views.

The advantages of my invention will be found to reside in a valve in which the flushing action is constant and not spasmodic, and in which leakage is prevented and also sticking or binding and detonation of the valve overcome.

The device may be greatly modified in detail of construction without departing from my real invention, as will be apparent to those skilled in the art.

Having thus described my invention, what I claim and desire to secure by Letters Patent is:

1. In a flushing valve, a casing having inlet and outlet ports, a valve controlling one of said ports, a piston in said casing controlling said valve, a relief chamber above said piston, a valved port connecting said relief chamber and the piston chamber, a drainage passage from said relief chamber to the outlet side of the valve having a restricted or jet discharge port at its delivery end, and a baffle on the upstream side of

said jet discharge port at its junction with the outlet passage to divert the outlet stream, prevent its backing up into said drainage passage, and tend to produce a 35 vacuum in said drainage passage.

2. In a flushing valve, a main casing having inlet and outlet ports, a valve having a series of stepped flat faces to effect a graduated control, controlling one of said 40 ports, a piston having a feed passage controlling said valve, a relief chamber above the piston chamber having a valved connection therewith, and a tubular feed plug in said piston feed passage having side ports 45 in its upper end.

3. In a flushing valve, a main casing having inlet and outlet ports, a piston valve controlling one of said ports and having a feed passage therethrough, a centering stem 50 for said valve, a cross-strut in said casing to receive and guide said stem, a relief chamber above the piston chamber and connected therewith by a valved port, and an adjustable tubular feed plug in the top of 55 said piston having a feed kerf in its top.

In testimony whereof, I have hereunto set my hand.

THOMAS F. PAYNE.
